UNITED STATES PATENT OFFICE

CHARLES LOUIS BAUDRY DE SAUNIER, OF PARIS, FRANCE

ELECTRIC CURRENT PLUG

Application filed June 18, 1929, Serial No. 371,792, and in France July 3, 1928.

The present invention relates to an electric current plug.

Nearly all electric current plugs now on the market include a large number of small parts (screws, nuts, etc.) which are easily mislaid and which require, for fixing the wires on to their terminals, tools which are not always within reach (screwdrivers, spanners, pliers, etc.). In other plugs, each pole 10 is a metallic stud of socket or pin form, screwed into an insulating holder and gripping between the end thereof and the inside of the insulating holder, the bared end of the conductor.

15 These plugs are more readily mounted than the preceding ones but they likewise require a tool for tightening up the studs, which must be done with considerable force in order to lock the studs and firmly grip the conducting wire.

In accordance with the present invention, the electrode may rotate freely in a cavity in the holder into which protrudes the bared conducting wire which may thus be wound 25 about the electrode in said cavity, said electrode being then locked in the holder by means of a nut screwed on the end of the electrode and bearing against the holder.

For fixing the wire on the electrode, a hole 30 is drilled transversely through the latter or else said electrode is provided with a lateral tab.

The holder has a seat in which a projection carried by the electrode is lodged 35 to hold said electrode while the nut locking it in the holder is tightened up.

The invention will now be described with reference to the accompanying drawings which illustrate an embodiment thereof diagrammatically and by way of example.

In the drawings:

Fig. 1 is an outside elevation of an electrode.

Fig. 2 is a vertical section through the holder and the nut for assembling the electrode in the holder.

Fig. 3 is a vertical section of the parts in process of assembly.

Fig. 4 illustrates in similar manner the assembled plug pin.

Fig. 5 shows an outside elevation of a two-pin plug according to the invention.

Fig. 6 is a similar view to that of Fig. 4, the electrode forming a socket.

Fig. 7 is a vertical section through a socket 55 wherein is located a tab in which the end of the wire is wedged and

Fig. 8 illustrates said socket in outside elevation and at 90° to the preceding figure.

The electrode is constituted by a stud made 60 of conducting material and in the form of a pin or socket. In Fig. 1, said stud has been shown as a pin 1.

Said stud 1 carries a pin 2, above which an opening 3 is drilled right through the stud 65 1 which latter is screw-threaded at the top as at 4.

The pin is placed in a holder 5 of insulating material, ebonite for example, illustrated in Fig. 2. In the base of said holder is 70 formed an aperture 6 for the introduction of the stud 1 and has a transverse slot 7 in which the pin 2 can be lodged; a hole 8 is also provided in the side thereof; finally, a closure 9 made of the same substance may be fitted to 75 the upper portion of the holder. Said closure has an inner thread so as to form a blind nut and the tapping 10 enables it to screw over the thread 4 of the metallic pin as illustrated in Fig. 4. The diameter of the pin 1 80 is smaller than the inner diameter of the holder 5, whereby an inner chamber is formed enabling the wire to be wound on during assembly.

To connect a cable to said holder, the closure 9 is unscrewed to a certain extent so that the pin 2 may be taken out of the slot 7 in which it lies. The hole 3 is practically facing the hole 8, the stud 1 is rotated by hand to bring the hole 3 into register with the hole 8 and the bared end of the cable 11 is inserted into the hole 3. The stud 1 is rotated several times about its axis so as to wind thereon a certain quantity of cable 11 and thus prevent the end of the latter from slipping 95 out of the opening 3 as a result of pulling on said cable. The pin 2 is then put back into the slot 7 and the closure 9 screwed home until the stud is securely held in the holder as illustrated in Fig. 4, the wire can then no 100

longer become unfastened from the stud which can no longer rotate. It will thus be seen that no tool is required in assembling and that no small parts which may easily fall or be mislaid, need be mounted or screwed.

In Fig. 5, a holder 5' has been illustrated having two pins such as 1 so as to form a two-pole plug which may be substituted for the ordinary plugs wheresoever they are used.

A connection or socket plug may be formed in the same manner as the pin plug; such a plug has been illustrated in particular in Fig. 6. The stud 12, located in the holder 5, is constituted by a socket having a hole 13 at its upper portion for the passage of the wire, two tenons 14 and 15, located at the lower end thereof, are received in the slot 7 of the holder, the closure 9 again screws on to the upper portion of the socket and locks the latter in the holder as previously.

In Figs. 7 and 8, there has been illustrated a similar socket but wherein instead of providing an opening extending right through the socket to take the bared end of the wire, there has been struck up from the socket a tab 16 in which the end of the wire can be wedged as has been illustrated in Fig. 8, the wire being wound several times about the socket as previously, to prevent it from becoming unwound.

The various details of the current plugs described above can of course be substantially modified. Thus other means may be provided for fixing the wire on the socket or electrode; just as it is possible to substitute round or hexagonal discs, cones, etc., for the pin 2 or the tenons 14 and 15.

In any case, as has been stated above, the present invention consists in winding a wire about a stud forming a pin or socket, so as to fasten it to said stud, and then to lock said stud in its holder. The current plug thus formed is of very simple and absolutely dependable construction since the wires can be pulled without it being possible to free them from the stud on which they are mounted and the contacts are as reliable as they can be with the conventional plugs.

It should be observed that with the wires reaching the plug from the side, as illustrated in Fig. 5, there is no tendency, as with the ordinary plugs, to pull on the wire to draw the pins out of the sockets, a proceeding which little by little damages the portion of the wire fixed in the plug.

I claim:

1. In an electric current plug, the combination of a conducting stud, a holder adapted to accommodate said stud and allowing free rotation of said stud therein, a cable penetrating into said holder through an opening therein, means associated with said stud for receiving said cable in such position that said cable can be coiled round said stud by rotat-

ing the latter in said holder, means for retaining said stud within said holder, and means operative for a predetermined position of said stud within said holder, for holding said stud against rotation.

2. In an electric current plug, the combination of a conducting stud, a holder adapted to accommodate said stud and allowing free rotation of said stud therein, a cable penetrating into said holder through an opening therein, means associated with said stud for receiving said cable in such position that said cable can be coiled round said stud by rotating the latter in said holder, and a tapped closure for one end of said holder into which said stud is adapted to screw.

3. In an electric current plug, the combination of a conducting stud, a holder adapted to accommodate said stud and allowing free rotation of said stud therein, a cable penetrating into said holder through an opening therein, means associated with said stud for receiving said cable in such position that said cable can be coiled round said stud by rotating the latter in said holder, a tapped closure for one end of said holder into which said stud is adapted to screw, a projection carried by said stud, and a seat formed in the opposite end of said holder to said closure and with which said projection may engage to prevent rotation thereof, said pin and closure thus cooperating to hold said stud fixed in said holder.

4. In an electric current plug, the combination of a conducting stud, a holder adapted to accommodate said stud and allowing free rotation of said stud therein, a cable penetrating into said holder through an opening therein extending substantially perpendicularly to said stud, and received in a hole in said stud, means for retaining said stud within said holder, and means operative for a predetermined position of said stud within said holder, for holding said stud against rotation.

5. In an electric current plug, the combination of a conducting stud, a holder adapted to accommodate said stud and allowing free rotation of said stud therein, a cable penetrating into said holder through an opening therein extending substantially perpendicularly to said stud, and received in a hole passing substantially transversely through said stud, and a tapped closure for one end of said holder into which said stud is adapted to screw.

6. In an electric current plug, the combination of a conducting stud, a holder adapted to accommodate said stud and allowing free rotation of said stud therein, a cable penetrating into said holder through an opening therein, and received in a hole in said stud, a tapped closure for one end of said holder into which said stud is adapted to screw, a projection carried by said stud, and a seat

formed in the opposite end of said holder to said closure and with which said projection may engage to prevent rotation thereof, said pin and closure thus cooperating to hold said stud fixed in said holder.

- 5 7. In an electric current plug, the combination of a conducting stud, a holder adapted to accommodate said stud and allowing free rotation of said stud therein, a cable 10 penetrating into said holder through an opening therein, means associated with said stud for receiving said cable whereby said cable can be coiled round said stud by rotating the latter in said holder, a tapped closure 15 for one end of said holder into which said stud is adapted to screw, a projection carried by said stud, and a seat formed in the opposite end of said holder to said closure and with which said projection may engage, said 20 projection then extending through a slot formed in said holder, and which prevents rotation of said projection.
